ADOLPH PETZOLD, OF PHILADELPHIA, PENNSYLVANIA, ASSIGNOR TO JOHN H. BROMLEY AND EDWARD BROMLEY, OF SAME PLACE, COPARTNERS, TRADING AS JOHN BROMLEY & SONS.

DESIGN FOR A RUG.

SPECIFICATION forming part of Design No. 34,741, dated July 2, 1901.

Application filed June 8, 1901. Serial No. 63,811. Term of patent 3½ years

To all whom it may concern:

Be it known that I, ADOLPH PETZOLD, a citizen of the United States, residing at the city of Philadelphia, State of Pennsylvania, have 5 invented and produced a certain new and original Design for Rugs, of which the following is a full, clear, and exact description, reference being had to the accompanying drawing, forming a part of this specification.

10 My design is applicable to and intended for the surface ornamentation of woven rugs.

In its essentials it consists, as shown in the drawing, of a border figure upon a rectangular ground, said figure consisting of two 15 opposite straight side lines *a*, terminating at the four corners in curved lines *b*, connected

by opposite line figures *c* with floral corner-pieces *d*. A central border-line *e* of oval shape forms the field center, and within the same is an oblong pattern *f* of flowers and leaves. 20

I claim—

The design for a rug, substantially as shown and described.

In testimony whereof I have hereunto affixed my signature this 24th day of May, 25 A. D. 1901.

ADOLPH PETZOLD.
